UNITED STATES PATENT OFFICE.

HARRY H. HANCOCK, OF SWAMPSOFT, MASSACHUSETTS, ASSIGNOR OF ONE-HALF TO
ARTHUR S. WEBSTER, OF HALIFAX, MASSACHUSETTS.

LINING APPARATUS.

1,297,840.

Specification of Letters Patent. Patented Mar. 18, 1919.

Application filed March 5, 1918. Serial No. 220,490.

To all whom it may concern:

Be it known that I, HARRY H. HANCOCK, a citizen of the United States, residing at Swampscott, county of Essex, and State of Massachusetts, have invented certain new and useful Improvements in Lining Apparatus, of which the following is a clear, full, and exact description.

This invention relates to lining apparatus, and resides in certain improvements upon the construction shown, described and claimed in my co-pending application for patent on lining apparatus, filed Jan. 20, 1916, Ser. No. 73,133. More specifically, the improvements herein disclosed are for use in connection with machines for lining-up in printing plants, with a view to obtaining speed and accuracy in the method of lining up. One of the objects of the present invention is to perform the operation of lining up under actual printing conditions with the elimination of all waiting time of the press for final corrective moves.

Other objects of the invention are to provide improved means for pressing and smoothing out a sheet which is imposed upon the sheet receiving surface; to provide improved gages for accurately defining the position of the edges of the sheet to be lined up; to provide an improved construction of marker; and to improve machines of this class generally.

With these and other objects in view, my invention consists of certain features of construction and combinations of parts to be hereinafter described and then claimed with reference to the accompanying drawings illustrating a desirable embodiment of the invention, in which—

Figure 1 is a plan view of the machine, showing a sheet that has been ruled or lined up;

Fig. 2 is an enlarged transverse section on the line 2—2 Fig. 1, showing one of the carriages, a marker and concomitant parts in side elevation;

Fig. 3 is a broken detail sectional view of one end of one of the paper smoothing or pressing members;

Fig. 4 is a sectional side elevation showing one of the gages and manner of mounting the same in position;

Fig. 5 is a plan view of the same parts;

Fig. 6 is a broken plan view of one of the marker arms or shafts;

Fig. 7 is a transverse section thereof;

Fig. 8 is a side elevation of one of the improved markers;

Fig. 9 is a top view of the same;

Fig. 10 is an enlarged sectional detail of one of the markers taken in a plane between the side faces of the marker;

Fig. 11 is a section on line 11—11, Fig. 10; and

Fig. 12 is a transverse section through the collar of the marker.

The present improvements more specifically relate to such a machine as shown in the aforesaid application, although it will be obvious that the improvements can be used in machines generally of the same general class; and in connection with machines of the specific class, I prefer to use miniature lay-out sheets or charts constituting a layout on which the paged dimension, etc., can be placed so that the compositor can see at a glance the type measure to set the type; the make-up man the length to make the pages; the stone man the exact number of picas to place in the margins and gutters; the press-man the margin for both gripper and side gages of the press, and the line-up man can line up the sheets either before or after going to press.

Referring to the drawings, (Fig. 1), the frame 12 is provided with a sheet imposing plate or table surface 13 having a relatively soft covering 14 preferably of canvas, which is stretched taut over the said plate and constitutes an imposing surface for the sheet to be lined up. The said fabric covering 14 may be secured in any suitable manner so as to stretch it tightly over the upper surface of the plate. At adjacent sides of the frame 12 are guide rails 15, 16, which are secured at right angles to each other by mounting the adjacent ends of said rails in an angle stanchion 17 provided with suitable sockets to receive the ends of said rails, while the other ends of said rails are mounted in stanchions 18 and 19, said stanchions being secured to the frame. Adapted to slide on guide rail 15 is a carriage 20, while another carriage 21 slides on the other guide rail 16, said carriages being provided with operating handles 22, 23 respectively. Marker arms 24, 25 are swiveled at one end in corresponding carriages 20, 21, so that they may be rocked on said carriages by the manipulation of said handles, in the manner

substantially as shown in the aforesaid application. Said arms will extend at right angles to each other over the sheet imposing plate 13, and their outer ends are provided 5 with guide rollers 26 and 27 which travel upon said plate when the arms are shifted upon the guide rails.

These arms 24, 25 constitute supports for gangs of markers 28 and 29 respectively, 10 said markers being adapted to be set to desired position upon said arms. At the inner ends of the arms 24, 25, brackets 30 are mounted, and these brackets are longer than other brackets 31 which are mounted at the 15 other ends of said marker arms. Said brackets are adapted to support sheet presser or smoothing members, to which end a bar 32 rigidly connects the said brackets of each marker arm. The brackets 30 being longer 20 than the brackets 31, the said bar 32 will be arranged at an inclination to the arm on which it is mounted, and will be positioned in advance of the markers during the marking operation, so that said bar will extend 25 in substantially the same direction as the held edge of the sheet to be lined, as will appear hereinafter. Mounted upon the ends of each bar 32 are sleeves 33, 34, said sleeves being loose with respect to the bar and having 30 a slight movement on radial pins 35 on the bar, which pins project through holes in the sleeves. As said pins project upwardly, the sleeves 33 and 34 are permitted a slight up and down movement relatively 35 to the bar on which they are mounted, but said sleeves do not contact with the surface over which they run. Long helical springs 36, 37 are mounted one on each bar 32, and the ends of the outer convolutions of said 40 springs are engaged in said sleeves, and they may also have a friction fit over the adjacent ends of the sleeves.

The said helical springs 35, 36 constitute presser or smoothing members which are 45 adapted to travel in contact with the upper surface of the sheet imposed on the sheet imposing plate, and assuming that the sheet is held at two adjacent edges and that the markers and said presser members move in 50 a direction away from the said secured edges, the inclination of each presser member is such that there is a tendency to smooth out the sheet in a direction toward the free corner. The loose convolutions of the helical presser springs ride easily over the surface of the sheet without any tendency to injure the same, and the flexibility or resiliency of the springs has a tendency to draw the sheet in a direction away from both of 55 the secured edges thereof and in advance of the markers 24, 25, so that a definite position of said sheet with respect to said markers is assured, and the free convolutions of the helical presser members will yield to any 60 unevennesses should any be present in the 65

supporting surface for the sheet. As the marker arms are swiveled on their carriages, the same may be rocked so as to raise the markers and the flexible presser members off the sheet when the marking has been 70 completed, so that the marker arm and the parts supported thereby may be returned to their former position without contact with the sheet. Ordinarily the sheet would be removed before the markers are returned for 75 another operation.

The sheets which are to be lined up or marked have their edges cut true as nearly as possible so that adjacent edges are at right angles to each other, each sheet being 80 at least substantially rectangular. This being the case, the sheet to be lined may be gaged upon the sheet imposing surface so that the lining up will be true and accurate. To gage the sheet, gages 38, 39, and 40 are 85 employed, although the number may of course be as many as required. Preferably two gages 38 and 39 are arranged for the gaging the feeding edge of the sheet, while one gage 40 only is necessary for the other 90 edge, which two edges are eventually secured in position by clamps 46. To enable the gages to be adjusted longitudinally of the edges of the sheet and to properly hold the gages in position relatively to said edges, 95 grooves 42 and 43 are provided in the frame 12, said grooves extending at right angles to each other and parallel with the guide rails 15 and 16. The construction of the grooves is shown clearly in Figs. 4 and 5, and 100 it will be seen from these figures that the outer wall 44 of each groove is inclined, the said wall slanting outwardly away from the bottom of the groove. The faces 45 of the gages are correspondingly inclined and said 105 gages are of a size to fit in the grooves, so that in placing a gage in its groove the inclined faces 44 and 45 coact to set and adjust the gaging face 44^a of the gage to a definite position, so that an edge of the sheet 110 may be abutted against the definitely located gaging face, and when all the gages have been properly set and the adjacent edges of a sheet abutted against the gaging faces of the gages, said sheet will be properly positioned for lining up. Above the face 44^a of each gage is a pair of fingers or projections 45^a, 45^b, which are spaced apart by the recess 45^c, so that the edge of the sheet can be viewed between the said projections and 115 it can be ascertained whether or not the edge of the sheet has been properly adjusted against the gaging face of the gage. Each gage also has a knurled finger piece 40^a to enable it to be easily handled. 120

Each marker arm 24, 25, is preferably graduated, the graduations being preferably spaced pica length apart. In addition to these graduations, each marker arm is preferably specially constructed for obtaining a 130

proper adjustment of the markers around each arm, as well as along it with reference to pica lengths. To this end each marker arm is provided with parallel grooves 47, 48, as shown in Figs. 6 and 7, said grooves being separated by an angle of about 60° , so that one of said grooves will be at the top of each arm while the other will be at the side of it. Groove 47 is intersected by transverse nicks or grooves 49, 49^a which are associated with the graduations and are spaced at regular intervals apart, preferably corresponding to half pica lengths. The said construction of each marker arm is adapted more particularly for holding and adjusting the improved construction of markers.

The markers are more clearly shown in Figs. 8 to 12 inclusive, and each marker comprises a collar 50 having a shank 51, the opposite side faces of said shank being set slightly in from the opposite faces of the collar, and the faces of the collar and of said shank will be parallel with each other. The face of each collar preferably constitutes an index member for setting the marker to a definite position on the marker arm. A toothed marker wheel is positioned upon the end of the shank opposite the collar and is mounted so that it may rotate, and is also yieldingly supported as in the manner shown and described in the aforesaid application. Also as described in said application, each marker wheel can have any one of four positions upon the shank, and Fig. 9 shows the marker wheel in one of said positions, that is to say, the wheel is so set that its marking edge will turn in a plane coincident with the plane of one face of the collar 50. The apertures of the collars of the markers are of such size as to enable the same to easily slide over and turn around the marker arm when the markers are shifted for changing their position.

Means are provided on each marker for setting the same relatively to the grooves 47, 48, in the marker arm and to the nicks 49. To this end each marker is provided with a lug 53 on the end of a headed locking pin 54 which is guided in a hole 55 in the bushing 56 which is screwed into the collar. Said bushing is screwed into a socket 57 which contains an expansion spring 58 arranged around the locking pin 54 and bearing upon the head thereof with a tendency to force the locking lug into the aperture of the collar. A knurled nut 59 is screwed on to the outer end of the locking pin 54 to provide means for holding said pin in position on the collar and to provide means for manually manipulating said locking pin. The function of the locking lug 53 is to engage in one of the grooves 47, 48 of the marker arm so that each marker may be adjusted to different positions about said arm. When the locking lug of a marker is set in the up-

per groove of the marker arm, the markers will be so positioned that when the marker arm is turned to marking position, the markers will extend toward the sheet imposing plate and the marker wheels will be brought upon the sheet to be marked. If it be desired to set certain of the markers so that they will not be brought to marking position when other of the markers are moved to marking position by the turning of the marker arm, each of the first named markers is turned upon the marker arm through an angle of 60° by manual manipulation of each marker. This is accomplished by taking hold of the milled nut 59 and pulling the locking lug 53 out of the upper groove of the marker arm and rotating the marker through an angle of 60° until its locking lug registers with the side groove on the marker arm, whereupon the hold on the nut 59 is released and the spring 58 will automatically engage the locking lug 53 with the side groove.

For co-operation with the graduated nicks 49, 49^a on each marker arm, each marker is provided with an operating lever 60 which is pivoted at 61 in a slot 62, so as to swing in a plane intermediate of the side or index faces of the collar, said lever being provided at its outer end with an operating button or knob 62, which is located away from one edge of the collar in convenient position to be engaged by the operator of the machine. The inner end of the lever 60 projects into the aperture of the collar 50 and engages in a slot 64, which extends through the lug and head of the locking pin 54, so that the said end of said lever may be engaged by the expansion spring 58. It will be seen that the expansion spring 58 serves two purposes. It acts not only to move the locking lug 53 to engage it with one of the grooves of the marker arm, but it acts upon the operating lever 60. Inasmuch as the inner end 65 of the lever 60 will thus be positioned so as to extend transversely of the marker shaft, said end will be forced by the spring 58 into engagement with either one of the nicks 49 of the marker shaft. When each marker is moved to a given position upon the marker arm, the inner end 65 of lever 60 establishes a locking engagement with the proper nick 49, thereby locking the marker against lateral movement. If the marker is to be then shifted along the marker arm to another position, the operator of the machine presses upon the button 62, thereby disengaging the locking end 65 of the lever from the nick which it engages, and the operator then shifts the marker along the arm until the desired position is obtained, when the button 62 is released and the end 65 of the lever automatically engages with the proper nick.

Preferably the marker construction comprises a collar, as 50, which has its greater dimension diametrically thereof, with its marker proper located and operating in the 5 plane of said greater, diametrical, dimension, and being disposed entirely to one side of the marker arms, 24 and 25, and with spring-actuated locking means on said collar located and operating in the plane of the 10 greater diametrical dimension of the collar, so that such means are parallel with and closely approximate the plane of the marking wheel or marker proper.

From the above it will be understood 15 that when the parts of the machine have been adjusted in readiness for operation, a sheet 66 to be lined is imposed on the plate 13 and two of its adjacent edges set to coincide with the inner faces of the gages 38, 20 39, and 40, said gages being movable to any desired position. When the sheet has been gaged, the clamps 46 are operated to clamp the gaged edges of the sheet, so that the sheet is held by its two adjacent edges, the 25 other edges being free, leaving a free corner. The marker arms are now operated by causing them to travel across the sheet one at a time, and in so traveling the yielding presser or smoothing members act to draw 30 the sheet or smooth it out toward the free corner thereof or on the bias with respect to either secured edge of the sheet.

Obviously the invention is susceptible of 35 a wide range of modification without departing from the spirit and scope thereof as claimed.

What I claim as new is:—

1. In apparatus of the class described, the 40 combination with means for holding a sheet at one of its edges, of traveling means adapted to be moved relatively to said sheet, and a flexible smoothing member mounted on said traveling means and extending for a considerable distance in the same general 45 direction as said held edge, said member being adapted to press along that surface of said sheet which is presented toward it.

2. In apparatus of the class described, the 50 combination with means for holding a sheet at two adjacent edges, of separate traveling means adapted to be moved relatively to said sheet, and a flexible smoothing member mounted on each of said traveling means and extending for a considerable distance in 55 the same general direction as said held edges, said members being adapted to press along that surface of said sheet which is presented toward them.

3. In apparatus of the class described, the 60 combination with means for holding a sheet at one of its edges, of traveling means adapted to be moved relatively to said sheet, and a flexible smoothing member mounted on said traveling means and extending for a 65 considerable distance at an inclination to

said held edge, said member being adapted to press along that surface of said sheet which is presented toward it.

4. In apparatus of the class described, the combination with means for holding a sheet 70 at one of its edges, of traveling means adapted to be moved relatively to said sheet, and a flexible smoothing member comprising a helically coiled spring loosely mounted on said traveling means and extending for a 75 considerable distance in the same general direction as said held edge, the convolutions of said member being adapted to press along that surface of said sheet which is presented toward it. 80

5. In apparatus of the class described, the combination with means for holding a sheet at one of its edges, of traveling means adapted to be moved relatively to said sheet, a bar carried by said traveling means and extending in the same general direction as said held edge, and a flexible smoothing member mounted on said bar and adapted to be moved along and in contact with said sheet. 90

6. In apparatus of the class described, the combination with means for holding a sheet 95 at one of its edges, of traveling means adapted to be moved relatively to said sheet, a bar carried by said traveling means and extending at an incline to said held edge, and a flexible smoothing member mounted on said bar and adapted to be moved along and in contact with said sheet.

7. In apparatus of the class described, the 100 combination with means for holding a sheet at one of its edges, of traveling means adapted to be moved relatively to said sheet, a bar carried by said traveling means and extending in the same general direction as said held edge, and a helically coiled spring 105 loosely mounted on said bar and adapted to be moved along and in contact with said sheet to smooth it out.

8. In apparatus of the class described, the 110 combination with a sheet imposing surface, of traveling means adapted to be moved substantially parallel with said surface, a flexible member, and means for loosely supporting said member on said traveling means, whereby said member is adapted to rest by gravity on a sheet imposed on said surface. 115

9. In apparatus of the class described, the combination with a sheet imposing surface, of traveling means adapted to be moved substantially parallel with said surface, a flexible member consisting of a helically coiled spring, and means for loosely supporting said member on said traveling means, whereby said member is adapted to rest by gravity on a sheet imposed on said surface. 120

10. In apparatus of the class described, the combination with a sheet-imposing surface and means for gripping one edge of a sheet to said surface, of traveling means 130

adapted to be moved at right angles to said edge and substantially parallel with said surface, a flexible member, and means for loosely supporting said member on said traveling means, whereby said member is adapted to rest by gravity on a sheet imposed on said surface, said member being inclined to the line of travel of said traveling means.

10 11. In apparatus of the class described, the combination with a sheet imposing plate, traveling means adapted to be moved relatively to said plate, and a sheet marker carried by said traveling means, of a flexible 15 smoothing member arranged in advance of said marker and adapted to smooth out a sheet on said plate as said marker progresses over it.

12. In apparatus of the class described, 20 the combination with a sheet imposing plate, means for holding a substantially rectangular sheet thereon at two adjacent edges of said sheet so as to leave one corner free, means adapted to travel away from one of 25 said edges, means adapted to travel away from the other of said edges, and means operated by said traveling means for smoothing out a sheet in a direction inclined from one of the other two remaining edges toward the other of said remaining edges, 30 whereby there is a tendency to smooth said sheet out in a direction toward its free corner.

13. In apparatus of the class described, 35 the combination with a sheet imposing plate, means for holding a substantially rectangular sheet thereon at two adjacent edges of said sheet so as to leave one corner free, means adapted to travel away from one of 40 said edges, means adapted to travel away from the other of said edges, a marker carried by each of said traveling means, and means operated by said traveling means for smoothing out a sheet in a direction inclined 45 from one of the other two remaining edges toward the other of said remaining edges, each of said markers being positioned back of its corresponding smoothing out means, whereby there is a tendency to smooth said 50 sheet out in advance of each marker but in a direction toward its free corner.

14. In apparatus of the class described, the combination of a sheet imposing plate, 55 means for holding two adjacent edges of a substantially rectangular sheet imposed on said plate, so as to leave a free corner, and means for smoothing out said sheet in a direction inclined to either of said edges but toward said free corner.

60 15. In apparatus of the class described, the combination of a sheet imposing plate, means for holding two adjacent edges of a substantially rectangular sheet imposed on said plate, so as to leave a free corner, and 65 flexible devices for smoothing out said sheet

in a direction inclined to either of said edges but toward said free corner.

16. In apparatus of the class described, the combination of a frame, a sheet imposing plate supported thereby, means for marking a rectangular sheet with lines at right angles to one of its edges, said frame having a way at right angles to the lining movement of said marking means, and movable gages applied to said way. 75

17. In apparatus of the class described, the combination with a frame, a sheet imposing plate supporting thereby, duplex means for marking a rectangular sheet with intersecting lines at right angles to two of 80 its adjacent edges, said frame having ways at right angles to the lining movement of said marking means, and movable gages applied to said ways.

18. In apparatus of the class described, 85 the combination of a frame, a sheet imposing plate supported thereby, means for marking a rectangular sheet with lines at right angles to one of its edges, said frame having a way at right angles to the lining 90 movement of said marking means, movable gages applied to said way, and means for holding said sheet by said edge.

19. In apparatus of the class described, the combination of a frame, a sheet imposing 95 plate supported thereby, means for marking a rectangular sheet with lines at right angles to one of its edges, said frame having a groove at right angles to the lining movement of said marking means, and movable 100 gages applied to said groove, one wall of said groove and corresponding faces of said gages coacting with a tendency to set said gages for a definite position of said edge.

20. In apparatus of the class described, 105 the combination of a frame, a sheet imposing plate supported thereby, means for marking a rectangular sheet with lines at right angles to one of its edges, said frame having a groove at right angles to the lining movement of said marking means, and movable 110 gages applied to said groove, one wall of said groove and corresponding faces of said gages coacting with a tendency to set said gages for a definite position of said edge, 115 and means for holding said sheet by said edge.

21. In apparatus of the class described, the combination of a plate with a sheet imposing surface, a plurality of markers, means 120 for carrying said markers and for moving them substantially parallel with said surface and in straight lines, and flexible presser means positioned in advance of said markers and operating on substantially the entire 125 width of a sheet to press on said sheet as said markers travel over its surface.

22. In apparatus of the class described, the combination of a plate with a sheet imposing surface, a plurality of markers, means 130

- for carrying said markers and for moving them substantially parallel with said surface and in straight lines, and presser means positioned in advance of said markers and operating in inclined position relatively to a line which passes through said markers on substantially the entire width of a sheet to press on said sheet as said markers travel over its surface.
- 10 23. In apparatus of the class described, the combination of means for supporting a marker arm, a marker arm thereon provided with parallel grooves, a marker shiftable about said arm, and a locking device on said marker engageable with either of said grooves.
- 20 24. In apparatus of the class described, the combination of a marker arm provided with transverse nicks forming graduations, a marker having a collar whereby it is mounted on and shiftable along said arm, said collar having its greater dimension diametrically thereof, and the marker proper being, and adapted to operate, in that plane of the greater, diametrical, dimension of said collar which is at right angles to said arm, and spring-actuated means on said collar and in the plane of its said greater, diametrical, dimension, for engagement with any one of said nicks, whereby said marker may be set in a definite position opposite any one of said nick-graduations.
- 30 25. In apparatus of the class described, the combination of a parallel grooved marker arm provided with transverse nicks forming graduations, a marker mounted on said arm, movable means on said marker for engagement with any one of said nicks, and a locking device for engaging one of said grooves.
- 40 26. In apparatus of the class described, the combination of a marker arm, a marker mounted thereon and shiftable along said arm, movable means for securing said marker in position when so shifted, and movable means for holding said marker against turning on said arm, said holding means being operable by said securing means.
- 50 27. In apparatus of the class described, the combination of a marker arm, a marker mounted thereon and extending in a plane at right angles thereto and having its marker-proper mounted in said plane, and located and operating entirely to one side of said arm, and spring-actuated means on said marker and operating in a plane transversely of said arm and which is parallel with and closely approximates the plane of said marker-proper, for automatically clutching and fixing said marker on said arm.
28. In apparatus of the class described, the combination of a marker arm, a marker mounted thereon, and spring-actuated means for clutching and fixing said marker on said arm at different angular positions about said arm.
29. In apparatus of the class described, the combination of a marker arm, a marker mounted thereon, and spring-actuated means comprising a manually operated lever, arranged transversely of said arm, for clutching and fixing said marker on said arm at different shifted positions along said arm, said lever being operable by a movement toward said arm, in order to release said clutching means.
30. In apparatus of the class described, the combination of means for holding an edge of a sheet to be lined, means for lining said so held sheet, and a flexible pressing and smoothing device for operating on said sheet in advance of said lining means when lining it.
31. In apparatus of the class described, the combination of a marker arm, a marker mounted thereon and shiftable along and about said arm, means for fixedly securing said marker in one or more shifted positions longitudinally of said arm, and additional means for holding said marker at one or more points about said arm and for fixedly securing it at either of said points.
32. In apparatus of the class described, the combination of a marker arm, a marker mounted thereon and shiftable along and about said arm, means for fixedly securing said marker in one or more shifted positions longitudinally of said arm, and additional means for holding said marker at one or more points about said arm and for fixedly securing it at either of said points, both of said securing means having clutch members which intersect each other.

Signed at New York, N. Y., this 28th day of February, 1918.

HARRY H. HANCOCK.
